UNITED STATES PATENT OFFICE

147,684

DESIGN FOR A HOUSING FOR A LOUD-SPEAKER AND COIN ACTUATED MECHANISM

George Phelps, Chicago, Ill., assignor to Communication Equipment and Engineering Company, Chicago, Ill., a corporation of Illinois

Application March 15, 1946, Serial No. 127,540

Term of patent 3½ years

(Cl. D26—14)

To all whom it may concern:

Be it known that I, George Phelps, residing at Chicago, in the county of Cook and State of Illinois, have invented a new, original, and ornamental Design for a Housing for a Loud Speaker and Coin Actuated Mechanism, of which the following is a specification, reference being had to the accompanying drawing, forming part thereof, in which;

Fig. 1 is a front perspective view of a housing for a loud speaker and coin actuated mechanism embodying my new design;

Fig. 2 is a front elevational view of the housing shown in Fig. 1;

Fig. 3 is a top plan view of the housing shown in Fig. 1;

Fig. 4 is a side elevational view of the housing shown in Fig. 1; and

Fig. 5 is a diagrammatic outline of a rear elevational view of the housing.

I claim:

The ornamental design for a housing for a loud speaker and coin actuated mechanism, substantially as shown.

GEORGE PHELPS.
